UNITED STATES PATENT OFFICE.

CHARLES M. POWER, OF PITTSBURGH, PENNSYLVANIA, ASSIGNOR TO UNITED STATES CHAIN & FORGING CO., OF PITTSBURGH, PENNSYLVANIA, A CORPORATION OF PENNSYLVANIA.

CROSS-CHAIN CONNECTER FOR ANTISKID DEVICES.

Application filed December 3, 1921. Serial No. 519,646.

To all whom it may concern:

Be it known that I, CHARLES M. POWER, a citizen of the United States, residing at Pittsburgh, in the county of Allegheny and 5 State of Pennsylvania, have invented certain new and useful Improvements in Cross-Chain Connecters for Antiskid Devices; and I do hereby declare the following to be a full, clear, and exact description of the 10 same, reference being had to the accompanying drawings, forming part of this specification.

This invention relates to anti-skid devices for vehicle tires, the object being to provide 15 a convenient and cheap means for securing or coupling the cross chains to the side chains, whereby the cross chains may be readily renewed when worn or broken, without requiring the use of special tools or 20 appliances for deforming the coupling members.

The invention consists in a coupling member or link wherein one end of the body portion is provided with an eye or opening for 25 co-operation with the end link of the cross chain and the other end of which is provided with a hook formed by a plurality of diverging spirals forming, together with the body portion spiral, entrance openings 30 through which the link of the side chain may be inserted in succession and by a spiral or twisting movement and from which it cannot readily escape when the companion links of the side chain are in normal position. 35

Referring to the accompanying drawings,

Figure 1 is a view of a section of an anti-skid device embodying the present invention;

Fig. 2 is a perspective view of one end of a cross chain with the coupling member thereon, and in dotted lines a portion of a side chain with the co-operating link in successive positions of insertion or removal;

Figs. 3 and 4 are a plan and an elevation of the coupling link.

The side and cross chains A and B of the anti-skid device are shown of conventional construction; that is to say, the links of the side chains A are formed up of wire or bar stock with an eye in one end in which the companion link is held and with straight side bars *a* and a rounded end which passes

through the eye of the other companion link. The cross chains are of the conventional welded and twisted link formation and each cross chain is provided with a coupling member at each end by which it is attached to the side chains. 55

The coupling member of the present invention which is also preferably formed of wire or bar stock has the body portion in the form of a loop C constituting an eye or opening for the engagement of the end link 60 of the cross chain. The two ends of the wire or bar stock are formed into a hook, the extremities of the hook being spread apart and down on each side of the body portion. The terminal of each bar of the link, therefore, forms an outwardly or laterally extending spiral E and together the two spirals 65 constitute the hook with which the side chain link co-operates.

This formation, it will be noted, provides 70 two entrance openings to the hook which are arranged at an acute angle to each other, and through which the side chain link must be passed in succession in assembling the 75 two members, and this assembling is possible only because of the possibility of moving the companion link of the side chain up 80 toward the eye end of the link, and inserting the side chain link more or less endwise through the entrance opening with a spiral 85 twisting motion.

Both of the terminals of the spirals are 90 preferably brought down into the plane of the body portion of the link, but are preferably not extended beyond that plane in order that no sharp projections may be 95 formed which would be liable to injure the tire or casing when the device is in use.

With this device the cross chains may be 100 readily attached or detached, but in practice it is found that there is little or no liability of their becoming accidentally disengaged and hence the device presents advantages of simplicity and security and at the same time obviates the bothersome necessity of providing special tools for the application or removal of worn or broken cross chains.

What is claimed is:

1. A hook link for the attachment of cross chains to the side chains of anti-skid devices, 105 having at one end an opening in the body portion for the attachment of the cross chain and at the other end plural hooks formed by

divergent spirals each extending upwardly from the body and having their terminals spaced on opposite sides of the body to form two spiral divergent hook entrance openings at opposite sides of the link body through which the side chain link may be successively passed.

2. A hook link for the attachment of cross chains to the side chains of anti-skid devices formed by a body loop for the end of the

cross chain and plural hooks at the opposite end formed by divergent spirals with their terminals extended into position on opposite sides of and spaced from the body portion, thereby forming plural hook entrance openings, one between each hook terminal and the body portion, said openings lying in different planes, each of said divergent spirals extending upwardly from said body. ¹⁵
